FACE PLATE CONSTRUCTION FOR SPRING SASH BALANCE

Axel W. Anderberg, Los Angeles, and Wilbur F. Blakemore, Beverly Hills, Calif., assignors to A. W. Anderberg Manufacturing Co., Los Angeles, Calif., a corporation of California

Application March 10, 1953, Serial No. 341,506

12 Claims. (Cl. 20—12)

The present invention relates generally to spring type sash balances of the type commonly used to counterbalance the weight of a vertically sliding sash; and the invention is more particularly concerned with improvements in the construction and configuration of the face plate of the sash balance.

It is conventional practice to place a sash balance of this type in the jamb of the window frame, the sash balance being set into the frame in such a manner that the surface of the face plate is substantially flush with the inner surface of the window frame so that each sash can slide up and down over the sash balance. In the ordinary double-hung window there are two sashes within the frame; and these are guided on one side by a vertical parting bead which is a narrow strip of wood mounted on the jamb of the window frame by being set into a groove in the jamb. The parting bead in conventional practice is continuous from the top to the bottom of the frame and is notched where it passes over the sash balance. In actual practice, the parting bead is often broken in the process of notching it because the notching so reduces the cross section that the bead is easily broken at the notch, unless the grain of the wood lies in such direction as to be favorable to notching. The broken bead is discarded and another one cut.

Considerable time is required to carefully and properly notch a parting bead for this purpose, although the operation is essentially a simple one. If the job is not carefully done, there may be considerable clearance between the bead and the sash balance through which air can pass; and even with care exercised in fitting it is not possible to eliminate all such air leakage. For this reason it has not been considered practical to weatherstrip double-hung windows using a spring type sash balance and the use of this balance is therefore looked upon with disfavor in colder climates where weatherstripping of the windows is desired.

Another marked disadvantage of the conventional construction comes to light when it is necessary to remove a sash balance for any reason, as when a spring breaks and a new unit is required as a replacement for the old one. Because the parting strip is continuous and passes over the sash balance, it is necessary to remove the parting strip as a preliminary step to removing the sash balance. In turn, this can be accomplished only by first removing the trim molding inside the frame so that the inner sash can be taken out of the frame. While this is not a particularly difficult operation, yet it requires considerable care and time to remove the molding from the window without irreparably scarring and damaging the frame; and even with the greatest of care, it is usually necessary to repaint the entire window frame and trim in order to remove signs of the repair work.

Thus it is a general object of our invention to modify the conventional type of parting bead where it passes over a spring type sash balance to eliminate time and labor spent in fitting and to make for easier removal of the bead.

2

It is also an object of our invention to construct the face plate of the conventional spring type sash balance in such a manner that an element carried by the face plate can serve as a parting bead for the length of the balance.

It is a further object of our invention to modify the conventional sash balance so that there is no air leakage around or past the parting bead or equivalent member where it passes over the sash balance, thus simplifying the problem of weatherstripping the sash.

These and other objects of our invention have been attained in a sash balance constructed according to our invention by providing on the face plate, which is fastened to the jamb of the frame, a longitudinally extending rib that projects outwardly from and is secured to the face plate. This rib is in alignment with the conventional parting bead carried in the jamb above and below the sash balance so that the continuity of the conventional wooden parting bead is interrupted and the gap between the ends of the wooden bead is bridged entirely by this rib carried by the face plate. The rib conforms in size and shape to the parting bead to perform the functions of the bead. The rib may be either adjustably or rigidly secured to the face plate in any one of a number of ways, as by separate fastening means or by being formed as an integral part of the face plate. If a separable member is attached to the face plate, then a completely air tight fit between the face plate and the rib may, if desired, be achieved by placing a thin layer of suitable sealing material between the rib and the outer surface of the face plate.

This novel construction has several advantages. Not only is it easier and quicker to install sash since the operation of notching the parting bead is entirely eliminated, but an airtight fit at the sash balance is obtained so that there is no problem of air leakage with usual kinds of weatherstripping. Furthermore, since the parting bead is now in two separate sections, one at either side of the rib carried on the balance, each section of the bead can be removed without disturbing either sash and it is not ordinarily necessary to remove either sash from the frame in order to change the balance. These advantages are discussed in further detail in the description below.

Although we show the sash balance in the vertical side member of the window frame, we are not necessarily limited to that location as balances are sometimes in the horizontal head member, often termed the "head jamb," of the frame which also has a parting bead in the usual construction. Our invention may also be utilized when the balance is in the head above the sashes. Consequently the term "jamb" as used herein is used in a generic sense to refer to either the side jamb or head jamb of a window frame.

How the above objects and advantages of our invention, as well as others not particularly referred to herein, are attained will be better understood by reference to the following description and to the annexed drawings, in which:

Fig. 1 is a fragmentary vertical section through the side jamb of a window frame, showing a sash balance embodying a preferred form of our invention set into the window frame and also showing a corner of each of the upper and lower sash in the frame;

Fig. 2 is a fragmentary elevation of the window frame jamb and sash balance as viewed from the right of Fig. 1 with the sashes removed;

Fig. 3 is a vertical median section on line 3—3 of Fig. 2;

Fig. 4 is an enlarged fragmentary side elevation of the sash balance showing the ends only of the face plate and attached rib of Fig. 3;

Fig. 5 is a top end view of the sash balance with its cover plate and attached rib formed as in Fig. 3;

Fig. 6 is a perspective view of a preferred form of detachable rib, shown in Figs. 1-5, removed from the cover plate of the sash balance;

Fig. 7 is a transverse cross section of the cover plate taken above the spring housing showing the use with a rib of the type shown in Fig. 5 of a layer of a sealing material between the rib and face plate;

Fig. 8 is a view similar to Fig. 3 showing a modified form of our invention;

Fig. 9 is a top end view of the sash balance shown in Fig. 8;

Fig. 10 is a perspective view of the modified form of detachable rib shown in Fig. 8;

Fig. 11 is a transverse section through a sash balance showing an integral rib on the cover plate; and

Fig. 12 is a transverse section, similar to Fig. 7, showing another modified form of our invention.

Referring now to the drawings, there is shown in Fig. 1 a spring type sash balance, generally indicated at 10, mounted in place in the jamb 12 of a window frame. It is conventional practice to cut a rectangular opening 14 in the jamb to receive the sash balance, permitting the sash balance to be mounted in such a manner that face plate 15 is substantially flush with the inner surface of the jamb facing the window sash. As shown particularly in Figs. 1 and 2, face plate 15 extends both above and below the main body of the sash balance to overlap the jamb for a short distance. The face plate is fastened to the jamb by any suitable means, such as nails 16.

The details of construction of the sash balance are in no way limitative upon the present invention; but in order to make a complete disclosure of our invention we show herein a spring type sash balance 10 such as is described more fully in the co-pending application of Axel W. Anderberg, Ser. No. 196,320, filed November 17, 1950 and which became Patent No. 2,644,193 on July 7, 1953 on "Spring Sash Balance." In general, the sash balance includes a pair of drums 18 each of which is rotatably mounted upon a hub 20. Inside each drum is a spiral spring, not shown in the drawings, which connects the rotating drum to the stationary hub and tends to rotate the drum about the hub in a given direction. Wound around the outside of each drum 18 is a cable 22 which at one end extends out of and below the balance. Each cable 22 is connected to one of the sash in any suitable way, as by a metal angle clip 23 fastened to the free end of the cable. In Fig. 1 one clip 23 is shown in place at the lower corner of upper sash 24. A similar clip, not shown in the drawing, connects the other cable 22 to a lower corner of lower sash 25. It will be seen from Fig. 1 that the two cables extend downwardly between the face of jamb 12 and the sash to which they are connected, there being sufficient clearance between the sash and jamb for this purpose.

The two drums of the sash balance are enclosed by a housing or cover plate 26 which is connected to face plate 15 by any suitable means, but preferably by being connected to one end of each of the two hubs 20, the other end of each hub being connected to the face plate. Each end of the hubs has a pair of projections or lugs 20a that project through the face plate or cover, as the case may be, and are then flattened or upset to rivet the hub to the cover and the face plate.

Jamb 12 is conventionally provided with a normally vertical, longitudinally extending groove 28 into which parting bead 29 is inserted. As seen clearly in Fig. 2, both groove 28 and parting bead 29 are interrupted in their continuity by the presence of the sash balance, normally located near or a short distance above their midpoint. The parting bead 29 is here in two separate and independent sections, one above and the other below the sash balance.

The purpose of the parting bead is to serve as a guide for the sashes as they slide up and down between open and closed positions. The sash are offset laterally, as shown in Fig. 2 so that one sash lies at each side of the parting bead. Upper sash 24, which is normally nearer the outside of the window, lies between the parting bead and molding 30. Lower sash 25 is on the other or inner side of parting bead 29 and is held between it and molding 31 along the inside edge of the window jamb. The sash are suitably shaped where they overlap in order to meet and prevent passage of air through the window, as is conventional and well known.

In order to bridge the gap between the upper length of parting bead 29 and the corresponding lower length, face plate 15 is provided with a centrally located, longitudinally extending rib 33 which, generally speaking, may be secured to the face plate in any one of several ways, as will be explained later in greater detail. This rib is in vertical alignment with the two sections of parting bead; and the rib extends over the full length of the face plate and projects a short distance above and below the face plate. The upper parting bead 29 abuts, or substantially so, upper end of the rib and the lower length of parting bead 29 abuts, or nearly so, the lower end of the rib. Parting bead 29 is cut to the proper length at the job site.

In this preferred embodiment, rib 33 is a separate U-shaped member having edges 33a that lie in a common plane, as shown in Fig. 6. When in place on the face plate, the rib is a hollow member. It is provided at one end with two small integral lugs or ears 34, having straight sides, that overhang the end of the face plate, as seen especially at the upper end of Fig. 4. At the other end, the rib has two hook-shaped integral lugs or ears 35, the open part 35a of the hook being preferably rectangularly shaped to receive snugly one end of face plate 15, as shown at the lower end of Fig. 4. Between lugs 34 and preferably extending just beyond them, there is a curved leaf spring 36 that is attached to the rib by a rivet 37 or any other suitable means. The spring leaf is adapted to slide over the end edge of the face plate and bear against the face plate. The two sets of lugs resist movement of the rib longitudinally relative to the face plate; and spring leaf 36, when in place as in Figs. 3 and 4, resists movement of the rib normal to the surface of the face plate. At the same time, the rib is able to slide over the surface of the face plate, though restrained by the frictional engagement of the lugs 34 and 35 and spring leaf 36 with the face plate.

To attach the rib to the face plate, lugs 35 are hooked over one end of the face plate which is seated in openings 35a of the lugs as the rib is rocked toward the face plate to bring edges 33a into engagement with the outer surface of the face plate. Lugs 34 are properly spaced from lugs 35 to just clear and pass over the edge of the face plate at the opposite end. By pressing on the end of rib 33, leaf spring 36 is raised slightly and slips over the end of the face plate. Because of its curved shape, the overhanging end of the leaf spring snaps down to a position as in Fig. 4 in which it resists movement in the opposite direction that would detach the rib from the face plate. However, by pressing upwardly or outwardly on the tip of spring 36, it disengages the face plate and allows the rib to be detached easily from the face plate.

The primary advantages of this construction are that the rib can be easily attached to the sash balance at the job site, which simplifies packaging, shipping, and assembly; and the frictional engagement with the face plate holds the rib in place with sufficient security yet allows the rib to be moved laterally of the face plate. When the sash balance is first nailed to the jamb and the rib then located properly with respect to groove 28 and attached 75 as described, suitable alignment is usually attained with-

out further fine adjustment. However, a small lateral adjustment may be needed to secure a final accurate vertical alignment of the rib with the sections of parting bead 29 above and below it. This may be accomplished by the workman on the job by tapping the rib at one side or the other with a hammer. By this construction, variations in the location of groove 28 relative to the edge of jamb 12 can be compensated for in a simple and effective manner.

When viewed endwise or in transverse cross section, the transverse dimensions of rib 33 conform closely to the corresponding transverse dimensions of the parting bead. As shown in Fig. 2, it is preferable that the side faces of the rib and parting bead are in vertical alignment in order to provide in effect a continuous guide against which each sash bears. Likewise, the height of the bead, which is the distance which it projects outwardly beyond the surface of face plate 15, conforms to the height of the parting bead so that a sash as it slides up and down moves over the rib with the same clearances as over the parting bead. Although in the overall dimensions the rib and parting bead conform to each other as closely as practical, the exact shape of them is immaterial. Within each of several large areas in this country, parting beads are almost universally of one size and shape. As between these areas, however, there may be appreciable variation in the dimensions of the standard parting bead. Consequently, no single size or shape is specified for the rib on the face plate since the rib will be made to conform to the parting bead with which it is used.

This is one reason why it is preferred to have the parting bead made separately from the face plate and easily attached thereto. The face plate itself can thus be standardized and requires only a single die. To form the rib, a blank is stamped from a sheet of flat metal and is then bent to the desired shape in cross-section in a selected one of a set of dies corresponding to the dimensions of a given parting bead; and it will thus be clear that this last set of dies is the only one which needs any variation in order to produce the necessary variety of shapes for the rib to match all parting beads that may be encountered.

In general, the face plates may be flat or embossed, as may be desired for any reason. However, it is preferable that the face plate have a zone in which the outer surface lies in a single plane, said flat zone extending for the full length of the face plate and being preferably at least slightly wider than the rib in order to simplify construction of the rib and improve the closeness of the fit between the rib and the outer surface of the face plate. As may be seen particularly in Fig. 2, portions 15a at each side of the face plate are slightly depressed, leaving two raised circular bosses 15b which are in the plane of the end sections of the plate which overlie jamb 12 in order to fasten the sash balance to the jamb. These two circular bosses and the two end sections are connected at tangency by narrow raised portions of the plate leaving a centrally located planar surface which is at all points wider than rib 33 and over which the rib is placed.

For ordinary purposes, the fit between the flat edges 33a of the rib and the outside surface of the face plate 15 within the planar zone just described may be sufficiently close not to permit objectionable leakage of air. However, if it is desired to eliminate all leakage at this point, a thin sealing layer 39, as shown in Fig. 7, may be inserted between the face plate and rib 33. This layer of sealing material 39 may be of any suitable substance, as for example felt, suitably treated paper, or the like.

As mentioned above, the rib may be secured to the face plate in any one of a number of ways. There is shown in Figs. 8, 9, and 10 a variational form of our invention in which a separate rib 33' is secured to the face plate by integral lugs 41 at each end of the rib (see Fig. 10). Lugs 41 are all similar in shape, and may be

similar to lugs 34, there being preferably two such lugs at each end. The face plate is slotted at each end to receive the lugs which pass through the slots 40 as shown in dotted lines in Fig. 9 and are then bent over to the solid line position to secure the rib in place. This arrangement results in a substantially rigid placement of the rib on the face plate, though a small amount of lateral movement could be obtained by making the slots in the face plate of suitable width. Rib 33' is preferably the same length as the face plate, and is therefore a little shorter than rib 33.

In another variational form of our invention shown in Fig. 11, rib 43 is secured in place by forming it as an integral portion of face plate 44. This may be done as 15 a drawing operation in the process of making the face plate. This construction has advantages from the standpoint of mass production when the rib is not too large, and of course it insures that there is no air leakage between the rib and the face plate. In this form of our invention, hub 20 is of sufficient diameter that the lugs 20a by which the hub is attached to the face plate, span rib 43, one lug 20a being at each side of the rib.

Another variational form of our invention is shown in Fig. 12 in which face plate 45 is formed in the same manner as face plate 15 (illustrated in Figs. 1 and 2) except that a plurality of suitably located holes are provided in the face plate through which may be passed screws 46. These screws are used to attach to the face plate solid rib 47 which is made from a suitable length of parting 30 bead 29 by cutting away the base portion of the parting bead which is normally inserted in groove 28. There is thus left the outer or exposed portion of the original parting bead which, when fastened to the face plate, has the effect of creating a continuous parting bead. This 35 piece of parting bead is attached to the face plate by wood screws 46 to serve as the rib. Of course, premolded solid ribs of plastic or other suitable material might be substituted instead of making rib 47 from the wood parting bead.

40 One of the chief advantages of our improved construction is the ease with which a sash balance 10 can be replaced. Upper and lower sash 24 and 25 are normally of about the same vertical dimension so that when the upper sash is moved down to its extreme lower position it 45 projects only a little above the top edge of sash 25 shown in Fig. 1. Then by removing nails 16 the sash balance is unfastened from the jamb of the window frame. Since there is no continuous parting bead over the sash balance, it is free to be removed from the jamb by tilting the upper end forwardly or inwardly of the frame and then lifting it up to remove the lower end from between the jamb and sash. There is ordinarily enough clearance between the sash and the jamb to remove each cable 22 by pulling it out from between the jamb and the sash. To facilitate 50 removal of the cables from inside the window, the lower length of parting bead 29 can be easily removed if desired either by sliding it upwardly after the sash balance is taken out of the jamb or by removing it parallel to the plane of the sash, as circumstances permit. A new balance is inserted in place by reversing these operations.

From the foregoing it will be apparent that there may be variations of our invention thought of by persons skilled in the art, yet within the spirit and scope of our invention. Consequently the above description is considered as being illustrative of rather than limitative upon the appended claims.

We claim:

1. In a spring-type sash balance having a face plate and adapted to be fastened to the jamb of a sash frame having a parting bead in the jamb, the balance being in a position to interrupt the parting bead, a longitudinally extending rib projecting outwardly from and fastened to the face plate and in alignment with the parting bead in the jamb above and below the sash balance.
2. A spring-type sash balance as in claim 1 in which

the transverse dimensions of the rib conform substantially to the transverse dimensions of the parting bead.

3. A spring-type sash balance as in claim 1 in which the rib extends substantially the full length of the face plate substantially to abut the parting bead above and below the face plate.

4. A spring-type sash balance as in claim 3 in which the face plate has a planar zone wider than the rib and extending the full length of the face plate.

5. A spring-type sash balance as in claim 1 in which the rib is a separate hollow member attached to the face plate.

6. A spring-type sash balance as in claim 1 in which the rib is a section of the parting bead of reduced height attached to the face plate.

7. A spring-type sash balance as in claim 1 which also includes means adjustably securing the rib to the face plate for movement of the rib laterally of the face plate.

8. A spring-type sash balance as in claim 1 in which the rib is provided with means frictionally engaging the face plate to mount the rib on the plate while permitting adjustment of the rib laterally of the plate.

9. A spring-type sash balance as in claim 1 in which the rib is provided with means for detachably securing it to the face plate.

10. A spring-type sash balance as in claim 9 in which the securing means includes a hook-shaped lug at one

end of the rib and a spring member at the other end adapted to engage the end of the face plate.

11. As an article of manufacture, an intermediate section of parting bead for use in a window frame having a recess for receiving a spring-type sash balance provided with a face plate, the sash balance being set into the recess in the frame with the face plate of the sash balance substantially flush with the exposed outer face of the frame, said frame having a groove above and below the recess to receive other sections of parting bead, comprising: a relatively narrow elongated body provided near each end with attaching means adapted to engage the face plate to secure the intermediate section of parting bead to the face plate, the intermediate section of parting bead being of such external dimensions as to form a substantial continuation of parting bead sections in the groove above and below the sash balance.

12. An article of manufacture as in claim 11 in which the intermediate section of parting bead is a hollow sheet metal member of U-shaped cross section.
